UNITED STATES PATENT OFFICE.

FERDINAND W. LULLOFF, OF COLBY, WISCONSIN.

TYPE-WRITER RIBBON-SHIFT.

1,151,488.

Specification of Letters Patent. Patented Aug. 24, 1915.

Application filed January 4, 1915. Serial No. 465.

To all whom it may concern:

Be it known that I, FERDINAND W. LULLOFF, citizen of the United States, residing at Colby, in the county of Marathon and State of Wisconsin, have invented certain new and useful Improvements in Type-Writer Ribbon-Shifts; and I do hereby declare the following to be a full, clear, and exact description of the invention, such as will enable others skilled in the art to which it appertains to make and use the same.

This invention relates to typewriting machines, and more especially to the ribbon mechanism thereof; and the object of the same is to produce improved means for shifting the ribbon so that it will vibrate through different paths.

Heretofore devices of this same general character and for the same general purpose have been patented and applied to different typewriting machines, but I observe that the means for shifting or varying the paths through which the ribbon may be subsequently vibrated automatically, are complicated, sometimes involve the use of another key and the mechanism connecting said means with the key, and often throw additional weight onto the parts which vibrate and therefore additional load onto the machine.

The purpose of the present invention is to provide a shifting device which is carried on the bracket whereon the vibrator is mounted, so that when said device is actuated it moves the base of the vibrator along a guide on said bracket and adds nothing whatever to the vibrating mechanism itself by way of either weight or complication.

Another or subsidiary purpose of the present invention is to provide extremely simple means for locking the shifting device in either of its limits of movement.

A third purpose of the present invention is to provide extremely simple means whereby the entire attachment can be removed from the typewriting machine.

With the above objects in view, the invention consists in the details hereinafter more fully described and claimed and as shown in the drawings wherein:

Figure 1 is a side elevation of this invention as applied to the parts of an Oliver typewriter, showing the base as set forward and the ribbon guide as retracted. Fig. 2 is a vertical section on the line 2—2 of Fig. 1. Fig. 3 is a plan view of this invention show-

ing the base as set backward and the ribbon guide as projected forward. Fig. 4 is a bottom plan view, with a section of the bracket on about the line 4—4 of Fig. 1.

In the accompanying drawings I have diagrammatically illustrated the roller or platen P, an indicating finger F lying over the same to show the position on the paper where the next type will strike, and the ribbon mechanism M by means of which the ribbon R is held in position over the platen so that the descending type drives it against the paper, which ribbon mechanism M is moved backward after the type has made its stroke, so that the operator may see the imprint of the character upon the paper. For the Oliver typewriter, these parts may be briefly described as follows: On a bracket 1 attached to a suitable part of the framework is mounted a base 2 having a post 3 rising from its rear end and a pair of ears 4 rising from its forward end. Pivoted at 5 to the post is a link 6, and mounted in bearings through the ears is a rock shaft 7 from which rises rigidly a forward link 8 standing strictly parallel with the link 6. The links are pivotally connected at their upper ends respectively at 9 and 10 with a Y-shaped fork 11 whose forward arms carry eyes 12 through which moves the ribbon R.

I have not thought it necessary to show the ribbon spools on which this ribbon is mounted, nor the mechanism for turning them. The ribbon itself may be in one color or two as usual. If in one color, continued use of the machine wears one edge and it becomes desirable in time to shift the paths through which the ribbon vibrates (by mechanism described below) so that the wear will fall on the ribbon near its other edge. If said ribbon is in two colors, then it becomes desirable at times to shift the path so that the type will strike upon the red portion of the ribbon, rather than upon the black portion as usual, assuming of course that the ribbon is in red and black.

As illustrated herewith, the end of the rock shaft 7 carries a crank 13 to which is attached the reciprocating rod 14 leading down to the universal bar of the typewriter; and, as well known in this class of devices, the construction is such that the ribbon mechanism M is automatically vibrated back and forth so as to retract the ribbon and permit the operator to see the paper, or to project the ribbon and permit the type to strike upon it every

time it makes a blow. The shifting mechanism moves the entire ribbon mechanism so that, when the operator desires to use the other edge of the ribbon or the other color 5 on the ribbon, the latter is moved from a different point and to a different point at each vibration, yet it is always passed under the type before the latter descends.

Coming now to the details of the present 10 invention, the top of the bracket is provided with a guide 20, herein shown as a groove having under-cut edges, and within this guide moves a slide 21 upon which the base 2 is secured in any suitable means—possibly 15 removably if desired. The front end of the slide is flush with the front end of the base, but the rear end of the slide projects beyond the rear end of the base as seen in Fig. 1, for a purpose yet to appear. Secured be- 20neath the bottom of the bracket, as by a screw 22, is a sector plate 23 on which at 24 is pivoted an L-shaped lever 25, its short arm 26 projecting laterally beneath the inner end of the slide 21 and being slotted as 25 at 27 to receive a screw or pin 28 depending from said slide, and its long arm projecting toward the operator and having a handle 29. The sector plate has rising from its inner end two studs 30 and 31, whereof one may 30 be in red and the other in black to indicate the different edges of the ribbon; and be- 35tween these studs the long arm of the lever moves as it is swung to one side or the other by means of its handle. The curved edge of the sector also has an up-struck tongue or lug 33 midway between these studs, over which the long arm of the lever rides as it is moved from one extreme position to the other; and the function of this lug is to 40 hold the lever in either extreme position.

With this construction of parts, the operation of shifting the ribbon mechanism is instantaneously accomplished by moving the lever from its position at one side of the lug 45 and against one pin or stud, over to its position at the other side of the lug and against the other stud or pin. This causes its inner arm to draw out or to push in the slide 21, which moves freely within the groove at the 50 top of the bracket, and as the slide carries the ribbon mechanism M the latter is of course moved with it. Meanwhile the vibrating mechanism 14 is uninterrupted in its action, as will be clear.

55 My invention adds nothing to the complica-
tion or weight of the ribbon mechanism itself. By withdrawing the screw 22 the sector plate and lever can be taken off of the bracket, and then the slide and the entire 60 mechanism M carried by it can be with-
drawn from the bracket for inspection and repair; and these parts can be restored in a few minutes' time and without the necessity for using any special tools.

56 The ribbon mechanism may have its usual

or any preferred construction, is extremely light, and is vibrated by the reciprocations of the rod 14 in the usual manner. The length of the crank 13 and the path through which the rod 14 vibrates, control the length 70 of the path through which the ribbon moves, whether the mechanism M is adjusted forward or backward. I find the pins and the intermediate lug on the sector plate ex- 75 tremely useful, because the color of the former may be made to designate the color which the adjustment will cause the type- 80 writing to assume, and the lug holds the lever in either extreme position so that it cannot become accidentally displaced by rea- 85 son of vibration. The weight of the attachment is entirely borne by the bracket, and the latter is mounted rigidly on the frame- 90 work.

What is claimed as new is:

1. The combination with the ribbon-carrying mechanism of a typewriting machine, and a support therefor including a substantially flat base; of means for slidably supporting said base, a fixed sector having pins 90 near the extremities of its curved edge and a lug between said pins, and a lever pivoted on the sector with one arm moving between said pins and over said lug and the other arm connected with said base. 95

2. The combination with the ribbon-carrying mechanism of a typewriting machine, and a support therefor including a substantially flat base; of a bracket having a guide, a slide secured to the base and movably mounted in said guide, a sector plate secured to the bracket, a lever pivoted to said sector plate with one arm projecting past the curved edge thereof, and connections between its other arm and said slide. 100

105 3. The combination with the ribbon-carrying mechanism of a typewriting machine, and a support therefor including a substantially flat base; of a bracket having a guide beneath said base, a slide secured beneath the base and movably mounted in said guide, a sector plate secured to the bracket and standing beneath said slide, an L-shaped lever pivoted at its angle on said sector plate with its long arm projecting over the curved edge thereof, and connections between the short arm and said slide. 110

115 4. The combination with the ribbon-carrying mechanism of a typewriting machine, and a support therefor including a substantially flat base; of a bracket standing beneath said base and having in its top a groove with under-cut edges, a slide fitting and movable in said groove, a sector plate detachably carried by said bracket, and a lever pivoted between its ends on said plate and having one end connected with said slide. 120

125 5. The combination with the ribbon-carry-
ing mechanism of a typewriting machine, 130

and a support therefor including a base; of a bracket standing beneath said base and having in its top a groove with under-cut edges, a slide movable in said groove, a sector plate having its inner end detachably secured beneath said bracket and its outer end curved, pins rising from the opposite ends of said curve, an L-shaped lever pivoted at its angle upon said plate with its long arm extending between said pins and its short arm having a slot, and a pin in said slide movably mounted in said slot, for the purpose set forth.

6. The combination with the ribbon-carry-

ing mechanism of a typewriting machine, a support therefor including a base, and means for vibrating the mechanism upon its support; of a bracket having a fixed guide for supporting said base, and manually operable means carried by the guide for adjusting the position of the base upon the guide, for the purpose set forth.

In testimony whereof I affix my signature in presence of two witnesses.

FERDINAND W. LULLOFF.
